(57) **CLAIM**

The ornamental design for a food container as shown and described.

DESCRIPTION

FIG. 1 is a perspective view of a food container, showing our new design.

FIG. 2 is a front view thereof.

FIG. 3 is a back view thereof.

FIG. 4 is a side view thereof.

FIG. 5 is another side view thereof, from the opposite side as FIG. 4.

FIG. 6 is a top view thereof; and,

FIG. 7 is a bottom view thereof.

The portions of the food container shown in dashed lines form no part of the claimed design.

The dash-dot-dash line illustrates an unclaimed boundary of the claimed design.
